UNITED STATES PATENT OFFICE.

JOHN VAN VLECK, OF NEW YORK, N. Y.

DESIGN FOR A CASE FOR ELECTRICAL MEASURING-INSTRUMENTS.

SPECIFICATION forming part of Design No. 23,297, dated May 22, 1894.

Application filed April 13, 1894. Serial No. 607,475. Term of patent 14 years.

all whom it may concern:

Be it known that I, JOHN VAN VLECK, of the city, county, and State of New York, have invented and produced a new and original design for Cases for Electrical Measuring-Instruments, of which the following is a specification.

The accompanying drawing represents an instrument case in perspective showing my design.

The leading and characteristic feature of my design is the peculiar configuration of the instrument case, showing one straight side and a side of irregular shape—the latter being first convex, then concave and then convex. The opposite sides of the case, one of which is shown at A, are flat and parallel.

The edge or periphery of the case is of much less width than the side A. The said periphery has first a convex curved portion, B. Immediately adjacent to the part B and forming a sharp angle therewith is a concave portion, E. Adjacent to the concave portion E is a convex portion, D. Extending between the part B and the part D is a straight side, C. 25

I claim—

The design for an electrical measuring instrument case substantially as herein shown and described.

JOHN VAN VLECK.
